UNITED STATES PATENT OFFICE.

JOHN MANOS, OF TORONTO, OHIO, ASSIGNOR OF ONE-FIFTH TO J. E. PARKER, OF TORONTO, OHIO.

COMBINED MOLD AND SCOOP.

Application filed March 3, 1925. Serial No. 12,812.

To all whom it may concern:

Be it known that I, JOHN MANOS, a citizen of the United States of America, and resident of Toronto, county of Jefferson, 5 and State of Ohio, have invented certain new and useful Improvements in Combined Molds and Scoops, of which the following is a specification.

This invention relates to a combination 10 mold and scoop for ice cream and similar confections, and it has for its primary object to provide a scoop and mold structure having novel and effective means for expelling therefrom the molded contents.

15 In describing the invention in detail, reference is herein had to the accompanying drawings, in which—

Figure 1 is a rear elevation of the invention; and—

20 Figure 2 is a longitudinal section of the same.

Referring to said drawings, 1 indicates a tubular member or casing, herein shown as of heart shape, but which may be made of 25 other preferred form. Said casing is rigidly carried by divergently inclined arms 2^a formed on the adjacent end of a handle 2. A slot or channel 3 extends from a point adjacent to the outer end of said handle to 30 and through the front end thereof, and disposed to operate in said slot is a lever 4. Said lever has its rear end portion pivotally mounted in the parallel handle members formed by said slot at a spaced distance 35 from the rear end of the latter and extends forward through a slot 5 of suitable length provided therefor in the adjacent wall of the casing 1 into underlying relation to a shiftable plate or piston-like plunger 6 40 which is fitted within said casing. A yoke 7 is formed on the front end of said lever, and the parallel members 7^a of said yoke are provided with short longitudinal slots, or oblong openings, 8 through which is directed a transverse pin 9 which has its opposite ends mounted in oppositely disposed lugs 10 rigidly carried on the under side of said plunger.

The outer end of the lever 4 is shaped to 50 form a gear segment, teeth 11 being formed thereon, as shown. Disposed in operative relation to said teeth are the corresponding teeth 12 of a gear segment formed on a lever or finger-piece 13 which is disposed 55 within the outer end of the handle slot 3,

being mounted upon a pivot pin 14. A spring 15 coiled upon said pivot pin, or upon oppositely disposed bosses 16 formed on the pivoted end of said finger-piece 13, has one member thereof disposed in underlying seated relation to the lever-like end of said finger-piece, and has its opposite member resting upon an inclined wall 17 which forms the rear terminus of the slot 3. 60

The spring 15 normally maintains the finger-piece 13 thrust forward in inclined relation to the handle, as shown in full lines in Fig. 2, whereby, through the intermediacy of the interengaged gear segments hereinbefore referred to, the lever 4 is held 70 in seated position within the handle slot for maintaining the plunger 6 in its retracted position at the bottom end of the casing 1. 75

The tool described is employed in the manner of a scoop and serves to mold the 80 material collected in the form of the interior of the casing. The so molded material is expelled from the casing by advance movement of the plunger, effected by pressing the finger-piece 13 inward against the 85 handle. Manifestly, such inward movement of the finger-piece acts through the interengaged gear segments to swing outward the lever 4 to which said plunger is attached, as aforesaid, said lever rotating on its pivot-pin 18, to the position indicated in broken lines in Fig. 2. Following the said forward actuation of the plunger, all of the parts are 90 returned to their normal retracted position by the force exerted by the then compressed 95 spring 15.

As herein shown, the handle 2 is made in one piece, the parallel members thereof being maintained in rigid relation by an integral back portion 2^b of saddle-like form. 95

What is claimed is—

1. An ice cream scoop comprising a tubular casing, means reciprocable within the casing for expelling the contents of the latter, a longitudinally slotted handle attached 100 to said casing, said casing having therein a slot in communication with the slot of said handle, a lever disposed in the handle slot and having pivotal connection with said expelling means, said lever being pivoted to 105 said handle adjacent to the rear end of said slot and having a gear segment on the rear end thereof, a pivoted member having a gear segment operatively engaged with that of said lever, and a spring associated with said 110

member serving to maintain the latter in outwardly thrust relation to said handle.

2. An ice cream scoop comprising a tubular casing, means reciprocable within the casing for expelling the contents of the latter, a longitudinally slotted handle attached to said casing, said casing having therein a slot in communication with the slot of said handle, a lever disposed in the handle slot and having pivotal connection with said expelling means, said lever being pivoted to said handle adjacent to the rear end of said

slot and having a gear segment on the rear end thereof, a finger-piece pivoted in said handle slot and having a gear segment interengaged with the segment of said lever, said finger-piece being depressible for swinging said lever to effect advance of said expelling means, and a spring associated with said finger-piece for returning the movable parts to their normal positions following actuation. 15

In testimony whereof, I affix my signature.
JOHN MANOS.
